SAFE CONSTRUCTION

Ralph W. Ledbetter, Anniston, Ala.

Application May 14, 1948, Serial No. 27,135

1 Claim. (Cl. 109—24)

1

This invention relates to safes in which valuables can be kept for storage and safely against theft, and fire, the same being a division of my co-pending application Serial Number 675,620, filed June 10, 1946, now abandoned, for Safe Construction.

The principal object of the invention is to provide a safe capable of being inexpensively manufactured and intended primarily for home or personal use, wherein, due to its weight and capability of being attached to some permanent structure, it cannot be easily removed from its predetermined site.

Another object of the invention is to provide a safe which can be readily molded into general form through the utilization of a metal jar, bottle or other liner, which in ultimate use will serve as the inner wall for the safe.

A further object of the invention is to provide a safe construction of substantially heavy weight, which can be either embedded in a wall or positioned adjacent some readily immovable structure and to which the same is attached in a secure manner.

Still a further object of the invention is to provide a method whereby concrete safes can be constructed by utilizing a jar, bottle or other receptacle as the core in molding the general construction and wherein the jar, bottle or receptacle will define the valuables' receiving chamber of the safe in the ultimate use of the structure.

These and various other objects and advantages of the invention will become apparent to the reader of the following description.

In the drawing:

Figure 1 is a perspective view of the safe;

Figure 2 is a cross section taken substantially on line 2—2 of Figure 1;

Figure 3 is a fragmentary detailed sectional view taken substantially on line 3—3 of Figure 1;

Figure 4 is a fragmentary detailed sectional view showing the manner in which one end of the securing chain is anchored.

Referring to the drawing, numeral 5 denotes a jar or bottle or in fact any other suitable receptacle which can be of metal, crockery or glass, and this receptacle is first positioned in a mold, suitably elevated from the bottom thereof, and around this receptacle is arranged individual or a continuous reinforcing rod 6, extending across the bottom, around the side and to the neck 7 of the receptacle.

A suitable form is used and imposed against the neck 7 of the receptacle, when pouring the concrete, so as to afford an outwardly flaring port

8, through which access may be had to the neck 7 of the receptacle 5.

When the concrete has been poured, allowed to set and removed from the mold (not shown), a block 9 of concrete serves as an encasing body for the receptacle 5, this affording considerable weight, to make it impracticable to be carried, insofar as weight is concerned.

Should the block 9 be broken, it would still be difficult to gain access to the receptacle 5, due to the presence of the reinforcing end protecting rod or rods 6.

A closure block 10 of concrete, reinforced by rods 11 at its innermost side portion is adapted to fit into the flaring port 8.

It is preferable that the front side of the block 9 be provided with a facing frame 12, inwardly of which plates 13 are disposed forming a metallic surfacing for the walls of the port 8. Pins or bolts 14 are disposed through openings in the plates 13 and into the concrete block 9 where anchoring elements 15 are provided, it being obvious that the frame 12 with its plate portions 13 are placed in position with the anchoring bolts 14 and members 15, before the concrete is poured.

Like bolts 16 and anchoring elements 17 are provided for a front metallic plate 18, disposed against the front side of the closure block 10.

Suitably anchored in the block 9 or secured to the metallic frame 12 is a hasp 19 through which the shackle of a padlock 20 is disposable, this padlock having a chain 21 disposed therefrom and connected to an I-bolt or the like 22, embedded as at 23 in the concrete block 9.

Obviously, this chain 21 may be disposed around a water or drain pipe or some other permanent structure to preclude the possibility of the safe being removed by an unauthorized person.

The front plate 18 carries a laterally projecting tongue 24 having a slot therein for receiving the hasp 19, outside of which, the padlock 20 is disposed in its connection with the hasp, thus allowing for the use of the padlock in not only maintaining the closure block 10 in place, but also embracing a water pipe, drain pipe or some other permanent structure to prevent easy transportation of the safe from its predetermined site.

At the opposite end of the closure block 10 from the padlock, are hinges 25 which have anchoring means 26 embedded in the block 9.

The ends of the block 9 may be molded to form hand receiving recesses 27, whereby the safe can be manually lifted.

Some form of readily removable closure 28 may be provided for the neck 7 of the receptacle 5, this being readily removable after the closure block 10 has been swung outwardly to opened position.

It can now be seen, that by molding the concrete 9 about the reinforcing end protective rod 6 and receptacle 5, a chamber is defined within the mass, which when the mass has set, will define a readily cleanable interior, much more desirable than if a core were used in forming the chamber, leaving a substantially rough interior. Further, by leaving the receptacle 5 within the concrete block, the operation of constructing the safe is considerably simplified with incidental mitigation of expense.

If desired, air spaces may be provided in the wall of the safe and the closure 28 for the neck of the bottle may be such as to make the chamber substantially water and vaporproof.

Due to the concrete external construction of the safe, the safe is substantially fireproof and its weight makes it impracticable for the structure to be easily moved by an unauthorized person from one point to another.

If desired, openings can be left in the bottom of the safe for receiving casters or rollers in order that the same can be transported by safe movers or other authorized persons.

While the foregoing description sets forth the invention in specific terms, it is to be understood that numerous changes in the shape, size and materials may be resorted to without departing from the spirit and scope of the invention as claimed hereinafter.

Having described the invention, what is claimed as new is:

A safe comprising a receptacle having a reduced neck, said neck defining an entrance to said receptacle, a block of protective material surrounding the receptacle and having an entrance opening in the forward wall encompassing said neck and into which the neck protrudes for a relatively short distance, said opening having flat inwardly converging walls, a cover plate for said forward wall, surface plates extending inwardly from the inner edges of said cover plate and closely overlying the walls of said opening, a closure for said opening, said closure having an inner face for snug disposition against the free end of the neck when the closure is in closed position and having side faces for like snug disposition against said surface plates when the closure is in closed position within said opening, and a surface plate on the outer side of said closure, said last-mentioned surface plate being in close registry with the inner edges of the cover plate when the closure is in closed position.

RALPH W. LEDBETTER.
